(57) CLAIM

The ornamental design for an hourglass table, as shown and described.

DESCRIPTION

FIG. 1 is a perspective view of the claimed design for an hourglass table;

FIG. 2 is a front view thereof;

FIG. 3 is a back view thereof;

FIG. 4 is a side view thereof;

FIG. 5 is the opposite side view thereof;

FIG. 6 is a top view thereof; and,

FIG. 7 is a bottom view thereof.

The broken lines showing the table feet, privacy panel, and tabletop illustrate portions of the hourglass table that form no part of the claimed design.
